UNITED STATES PATENT OFFICE.

EDWIN P. BRANDT, OF CASPER, WYOMING.

SNUBBER.

Application filed July 10, 1926. Serial No. 121,692.

This invention relates to devices for preventing rebound in motor vehicles after deflecting of the vehicle springs incident to travel over a rough roadway.

One of the important features of the invention is to provide a snubber of such a character, that the same can be readily applied to different types and sizes of vehicles, the parts of the snubber being reversible so as to permit the same to be used on either side of the car.

Another object of the invention is the provision of a snubber of the flexible cable or strap type embodying novel means connected with and engaging the strap or cable for limiting the travel thereof, said means being so constructed and arranged as to effectively act to check the rebound of the vehicle during the short limited travel of the strap.

Another object of the invention is the provision of friction shoes arranged in a novel manner for engaging the strap for checking the sliding movement thereof during the rebound of novel spring pressed levers operatively connected with the strap for acting against the movement of the strap according to the travel thereof.

A still further object of the invention is to provide a novel snubber of the above character which will be durable and efficient in use, one that will be simple and easy to manufacture and one which can be incorporated with a motor vehicle at a small cost.

With these and other objects in view, the invention consists in the novel construction, arrangement and formation of parts, as will be hereinafter more specifically described, claimed, and illustrated in the accompanying drawings, in which drawings a preferred embodiment of the invention has been shown.

Figure 1 is a side elevation of the improved snubber showing the same in operative position on a vehicle, only a sufficient portion of the vehicle being shown to illustrate the connection of the snubber with the chassis and axle,

Figure 2 is an edge elevation of the same showing the same connected in place to one of the side channel beams of the chassis,

Figure 3 is an inner side elevation of the snubber removed from the vehicle.

Figure 4 is a section through the snubber

illustrating the arrangement of the parts when the strap is not under tension,

Figure 5 is a similar view showing the strap under tension and the normal arrangement of the parts when the same is applied to a vehicle, the guide and shield plate for the friction shoes being shown in place,

Figure 6 is a bottom plan view of the main casting with the various operating parts positioned thereon,

Figure 7 is a section through the snubber taken on the line 7—7 of Figure 4 looking in the direction of the arrows,

Figure 8 is a detail perspective view of the main casting with the operating parts removed therefrom,

Figure 9 is a detail perspective view of one of the friction shoes,

Figure 10 is a detail perspective view of one of the resistance levers,

Figure 11 is a detail perspective view of the other resistance lever,

Referring to the drawings in detail, wherein similar reference characters designate corresponding parts throughout the several views, the letter A generally indicates one form of the improved snubber and B a portion of the vehicle with which it is associated. The vehicle B forms no part of the present invention and has simply been shown to illustrate the use of the snubber and only a fragment of one of the sides of the channel beams 10 and axle 11 has been shown.

The improved device A comprises a casting 15 which includes a disk shaped body plate 16 having formed on its outer face an attaching plate 17. The inner face of the plate 16 has formed thereon a hub 18, which in the present instance is provided with a pair of spaced radially extending guide openings 19 and 20 arranged at right angles to one another. Intermediate the slide openings 19 and 20, the hub 18 is provided with a relatively large cut out portion 21, the walls of which are arranged at right angles to one another. The axial center of the hub is provided with an opening 22 which communicates with the opening 21 and it is to be noted that the hub has its outer face spaced inwardly from the periphery of the disk 16. The plate 16 is provided with an axial internally threaded opening 23 for a purpose, which will be hereinafter more fully described. Outwardly extending

ears 24 and 25 are formed on the hub at the sides of the opening 21 and the plate 16 directly below the ears 24 and 25 is provided with openings 26 and 27 which are in alignment with the openings 28 and 29 formed in the said ears. Lugs 30 and 31 are carried by the side walls of the opening 21 as clearly shown in Figure 8 of the drawings.

10 Friction blocks 32 and 33 are slidably mounted respectively in the slide ways 19 and 20 and these friction blocks are normally urged outward radially from the hub by suitable expansion springs 34 which are coiled about a guide pin 35 secured to the inner walls of the guide ways 19 and 20. The outer ends of the springs 34 are received within relatively deep recesses 36 formed in the inner faces of the blocks and these recesses are of such a diameter so as to entirely house the springs and the pins 35 when the blocks are forced inwardly to their full extent. The blocks 32 and 33 at their outer ends are provided with arcuate 25 friction faces 37 and the blocks normally project beyond the hubs, but when the blocks are forced inward to their full extent the friction faces 37 will lie flush with the outer face of the hub.

30 A cover and guide plate 39 of segmental shape is secured to the hub and partially overlies the guideways 19 and 20 and the axial opening 22. The portion of the plate 39 which overlies the axial opening 22 is 35 provided with a suitable opening 40 which aligns with the internally threaded opening 23 of the plate and a suitable shaft 41 is connected with and extended through these openings. In order to resist the pull of the strap 42 directly levers 43 and 44 are provided. The inner end of the lever 43 is provided with a hinged barrel 45 and with pivot ears 46 at its outer end.

40 The opposite ends of the lever 44 are provided with pairs of pivot ears 47 and 48 respectively. The barrel 45 is placed between the pivot ears 47 and the stub shaft 41 is placed through the same and these levers are confined between the plate 16 and the plate 39 in the opening or space 21. The outer face of the lever 43 is provided with a socket 49 for the reception of an expansion spring which is fitted about the pin 30. The inner face of the lever 44 is provided with a 50 similar socket 51 for the reception of an expansion spring 52 which is fitted about a pin 53 carried by the inner face of the lever 43. It is to be noted that the inner face of the lever 43 is so formed as to permit a portion 55 thereof to ride into the lever 44 between the pivot ears 47 thereof.

60 The outer pair of ears 48 of the lever 44 receives a suitable removable pin 54 to which is clamped or otherwise secured to the strap 42 and this strap is placed between the

ears 46 of the lever 43 and then trained about the hub 18. The strap 42 is then trained under the pin 55 which is placed in the aligned openings 29 and 27 heretofore referred to. By this arrangement of the strap, it can be seen that the friction blocks 32 and 33 bear at all times against the inner face of the strap 42 thus tending to oppose the sliding movement thereof.

A protecting casing 60 is provided for housing the various operating parts so as to protect the same from dust, road grit and the like and this casing is fitted directly over the hub and is secured to the periphery of the plate 16 as at 61. The side wall of the casing 60 is provided with an opening or slot 62 through which the strap 42 is adapted to extend. The stub shaft 41 is preferably provided with lubricating ways 63 so as to permit the lubrication of the levers 43 and 44 in their swinging movement on the said shaft and grease can be forced into the passageway 63 by any desired means.

In applying the snubber in position, the screw stud 65 is provided and this stud is fitted through an opening in the side channel beam 10 and threaded into an opening 66 in the enlargement 17 provided for that purpose. A spacing collar 67 is placed on the screw stud between the beam 10 and the enlargement 17. A stop stud 68 is also threaded in the enlargement 17 for engaging the lower face of the channel beam 10 of the chassis so as to prevent rotation of the snubber beam and casting thereon.

After the device is applied as shown in Figure 2 of the drawings, the strap 42 is pulled around the axle 11 until spring 52 is compressed allowing the arm or lever 44 to come into engagement with the arm or lever 43 and the slide blocks are forced inwardly against the tension of the springs 34. The strap is now ready to be secured in place around the axle, and a suitable clamp 70 can be utilized for this purpose.

Figure 4 shows the position of the parts as above described. During the above adjustment the car must be without load.

The device as shown in the drawings is assembled for right rear or front left. To attach to left rear and right front it is merely necessary to remove the plates 39, pins 54 and 55 and place them in the holes in the ear 24 and in the ear 48, and remove the strap and reverse the levers 43 and 44 placing the springs 50 and 52 with spring 50 over the pins 31 and then replacing the strap.

When a load is placed in the car, the vehicle springs are compressed according to the weight. This compression of car springs causes the control strap 42 to relax the pressure upon the parts compressed, during the adjustment of the strap. When the

car frame has reached its lowest point of vehicle spring compression, the levers 43, 44 and the slide blocks 32 and 33 and the strap 42 will be in the position shown in Figure 4 of the drawings. As the body rises, the control strap 42 tightens and at the same time causes a friction effect on slide blocks 32 and 33 and springs 34, 50 and 52. On the rebound or rise of the vehicle body in position, the friction increases on the strap 42. When the body rises beyond point of original adjustment of the strap friction and resistance are increased by spring 50 coming into play. When driving on smooth roads, the device comes into action to relieve vibration. When the roads become rougher and the bumps greater, its resistance increases preventing violent spring reaction and shocks to passengers and cars.

10 Springs 52 should be sufficient resistance to take up all slack in the strap 42. The springs 34 should be less strength than the spring 50. Spring 50 should be of sufficient resistance to overcome combined resistance 20 of the springs 34 and 52. The pin 55 can have a roller mounted thereon and this pin and roller prevents the strap from pulling away from the friction face of the hub of the casting. The device can be applied to cars 25 a number of different ways, such as by turning the same upside down and pulling the strap over the pin 55 and its roller down to the axle. This application of the device functions in the same manner as in the first 30 position.

Another manner of attaching the snubber is as follows. The strap 42 can be attached directly to the lever 43 with lever 44 turned over to face in opposite direction and insert 40 spring 52 between the lever and the wall of the space 21. The strap is brought around the hub in the same manner as shown. The strap is brought over the pin 54 of lever 44 and the slide blocks in the same position 45 as shown.

By adopting the last position it is necessary to use other means of fastening the frame of the car. The device has great range owing to the various means by which 50 the same can be applied.

Changes in details may be made without departing from the spirit or scope of the invention, but:

What I claim as new is:

- 55 1. A device for preventing rebound in vehicles comprising a stationary hub adapted to be secured to the frame of a vehicle, a flexible cable trained about the hub, a pivoted spring pressed lever connected with the inner end of the flexible member to oppose movement thereon, the outer end of the flexible member being adapted to be attached to the axle of the vehicle, and a friction block engaging the flexible member at a point intermediate its length.
- 60 2. A device for preventing rebound in vehicles comprising a flexible member, a pivoted spring pressed lever carried by one portion of the vehicle and connected with the inner end of the flexible member to oppose movement thereof, the outer end of the flexible member being adapted to be connected to another portion of the vehicle movable relative to the first mentioned portion, and a friction member engaging the flexible member at a point intermediate its ends. 70
- 65 3. A snubber for motor vehicles comprising a casting having a hub provided with a cut out portion, a pair of levers pivotally connected together and to the hub at the axis thereof, a compression spring between the levers and a compression spring between one of the levers and the wall of the cut out portion, a flexible member detachably secured at its inner end to the first mentioned lever and trained about the hub, and means for securing the flexible member to the axle of the vehicle. 80
- 70 4. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 85
- 75 5. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 90
- 80 6. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 95
- 85 7. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 100
- 90 8. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 105
- 95 9. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 110
- 100 10. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 115
- 105 11. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 120
- 110 12. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 125
- 115 13. A snubber for motor vehicles comprising a casting including a hub, a pivoted lever carried by the hub, spring means normally urging the lever in one direction, a strap secured to the lever and trained about the hub, a friction block carried by the hub, spring means normally urging the block radially of the hub in engagement with the inner face of the strap, and means for securing the outer end of the strap to the axle of a vehicle. 130

the axis thereof, the levers being reversible relative to one another, a compression spring between the levers and a compression between one of the levers and the wall of the 5 cut out portion, a strap detachably secured at its inner end to the first mentioned lever and trained about the hub, a spring pressed radially urged friction block mounted in the slideway for engaging the strap, and 10 means for securing the strap to the axle of the vehicle.

8. In a snubber of the character described, a casting including a plate, a laterally projecting hub carried by one face of the plate, 15 means carried by the opposite face of the plate for permitting the attachment thereof to the chassis of the vehicle, the hub having a radially extending guideway and a segmental cut out portion, and laterally ex- 20 tended pivot ears formed on the hub at the opposite sides of the cut out portion.

9. A snubber for motor vehicles comprising a casting having a laterally projecting hub provided with a segmental cut out portion, a pair of pivoted levers connected together and to the hub at the axis thereof, the levers being reversible relative to one another, a compression spring between the levers and a compression spring between one of the levers and the wall of the cut out 25 portion, a flexible member detachably secured at its inner end to the first mentioned lever and trained about the hub, a removable guide for the flexible member adapted to be secured to the hub on either side of the cut 30 out portion, and means for securing the strap to the flexible member at the axle of the vehicle.

In testimony whereof I affix my signature.

EDWIN P. BRANDT.
